(57) **CLAIM**

The ornamental design for a pneumatic amplifier head, as shown and described.

DESCRIPTION

FIG. 1 is a perspective view of the pneumatic amplifier head. FIG. 2 is a right elevation of the pneumatic amplifier head, the left elevation being a mirror image thereof.

FIG. 3 is a front elevation of the pneumatic amplifier head.

FIG. 4 is a rear elevation of the pneumatic amplifier head.

FIG. 5 is a top plan view of the pneumatic amplifier head.

FIG. 6 is a bottom plan view of the pneumatic amplifier head; and,

FIG. 7 is a bottom perspective view of the pneumatic amplifier head.

The broken lines in the figures depict connection tubing and are illustrative of environment and not intended to form a part of the claimed design.
